UNITED STATES PATENT OFFICE.

FERDINAND PHILLIP TRAUTWEIN, OF LUTESVILLE, MISSOURI.

FLOUR BOLT AND DRESSER.

SPECIFICATION forming part of Letters Patent No. 448,283, dated March 17, 1891.

Application filed June 6, 1890. Serial No. 354,454. (No model.)

To all whom it may concern:

Be it known that I, FERDINAND PHILLIP TRAUTWEIN, a citizen of the United States, residing at Lutesville, in the county of Bol- 5 llinger and State of Missouri, have invented certain new and useful Improvements in Flour Bolts and Dressers; and I do declare the following to be a full, clear, and exact de- 10 scription of the invention, such as will enable others skilled in the art to which it appertains to make and use the same, reference be- 15 ing had to the accompanying drawings, and to the letters of reference marked thereon, which form a part of this specification.

15 This invention relates to certain new and useful improvements in flour-bolts; and it has for its object, among others, to provide an im- 20 proved device of this character wherein is em- ployed an inner revolving drum or cylinder provided with troughs or buckets for the pur- 25 pose of taking up the material and carrying it up and over and dropping or throwing it down and against the cloth on the downgoing side of the outer reel. The inner and outer cylinders are caused to revolve at different 30 rates of speed, the inner cylinder being set eccentric to the outer one, so as to revolve close to the cloth of the outer reel on the bottom and upon the upgoing side thereof, where- 35 40 by it will keep the material constantly in motion on the bottom of the cloth of the outside reel. I provide a strong and cheap skeleton frame for the outside reel, which gives great strength and very little obstruction on the in- side of the reel and none on the outside, leaving the reel in good shape for the use of a brush on the outside for cleaning the cloth.

Other objects and advantages of the invention will hereinafter appear, and the novel 45 features thereof will be specifically pointed out in the appended claims.

The novelty resides in the peculiarities of construction and the combinations, arrangement, and adaptation of parts, all as more 50 fully hereinafter described, shown in the drawings, and then particularly defined in the claims.

The invention is clearly illustrated in the accompanying drawings, which, with the letters of reference marked thereon, form a part 55 of this specification, and in which—

Figure 1 is a vertical longitudinal section

through a flour-bolt constructed in accordance with my invention. Fig. 2 is a vertical cross-section of the same.

55

Like letters of reference indicate like parts where they occur in both views.

Referring now to the details of the drawings by letter, A designates the casing, which may be of any well-known or preferred construction, and B is a conveyer box or trough in which works the conveyer C, of any desired form and designed to carry off the flour. More than one conveyer might be employed, if deemed necessary or desirable, although 60 only one is shown. The sides of the casing or chest has sloping incline from the outside inward, as shown in Fig. 2.

D is the outer cylinder or reel, which is formed of the heads a and b, connected by the 65 longitudinal bars c, which are joined by a plurality of rings or bands d, as many being employed as the length of the reel requires. These bands and longitudinal bars are arranged at suitable intervals and are designed 70 to support the surrounding cloth e.

E is a skeleton head over which the outer reel is sleeved, and this head is carried by 75 and moves with the tubular gudgeon f, which has a suitable bearing in the frame of the 80 casing or chest.

At the opposite end of the reel there is a skeleton head g, which is supported by in- 85 wardly-curved arms h to provide room for the inlet-spout F. The inside cylinder is of less length than the outer one, and this inner cyl- 90 95 100 inder G is provided with peripheral troughs or buckets i, which are adapted to gather up the material and carry it to the top, where it is let fall against the cloth of the outer reel, as will be readily understood. The heads a and b are simply bands of thin material of the same material and of the same thickness as the bands d and bars c, as seen in Figs. 1 and 2. The said bands, heads, and bars are halved together or otherwise connected at their points of intersection, so as to provide a smooth outer periphery, as seen in Fig. 2, so that no obstruction to a brush will be formed, and the inner surface will also be practically smooth. The netting can be better and more evenly stretched than where there are projections and will wear much longer. The head g is secured to the inner

face of the head *a*, and the head *E*, of small iron, as seen in Fig. 1, is secured to the inner faces of the longitudinal bar *c*. The shaft *H* of this inner cylinder is passed eccentrically 5 through the tubular gudgeon, so that the lower edge of the said inner cylinder will come in close contact with the cloth on the under side of the outer reel, so as to prevent clogging and caking of the material at this point.

10 The shaft of the conveyer is extended at one end and carries two sprocket-wheels *J J* of the same size. On the shaft of the inner cylinder is fixed a small sprocket-wheel *j*, and on one of the tubular gudgeons of the outer 15 reel is a large sprocket-wheel *K*, there being a drive-pulley *L* on the shaft of the inner cylinder, as shown.

M and *N* are sprocket-chains connecting the two sprocket-wheels on the conveyer-shaft 20 with the large and small sprocket-wheels on the shafts of the inner and outer cylinders, as shown, so that the said inner and outer cylinders are revolved at a different rate of speed.

Other means may be employed for imparting 25 the differential speeds to the inner and outer cylinders and various modifications in detail may be resorted to with regard to the other parts without departing from the spirit of the invention.

30 The parts above described may be made of any suitable material, part of metal and part of wood, or otherwise, as found most expedient.

In long reels I may sometimes employ driving means at the tail end of the conveyer and reel.

The operation is simple and will be readily understood. The bran escapes through the outlet *m* at the tail end of the machine.

What I claim as new is—

1. In a device of the character described, a 40 skeleton-reel support consisting of head-bands *a* and *b*, flat bands *d*, and longitudinal flat bars *c*, all of this material and all of uniform thickness, united at their points of intersection to form a smooth outer and inner periphery, substantially as shown and described.

2. In a device of the character described, a 45 skeleton cylindrical reel frame or support consisting of end bands *a* and *b*, longitudinal flat bars *c*, and flat bands *d*, united to form a 50 smooth outer and inner periphery, combined with the skeleton head secured to the band *a* and having inwardly-extending tubular gudgeons, and the skeleton head *E*, of angle-iron, secured to the bars *c* inside of the end band 55 *b* and carrying the tubular gudgeon *f*, all substantially as shown and described.

In testimony whereof I affix my signature in presence of two witnesses.

FERDINAND PHILLIP TRAUTWEIN.
